UNITED STATES PATENT OFFICE

134,815

DESIGN FOR A VELOCIPED FRAME MEMBER

William I. Smith, Goshen, Ind., assignor to The
Hettick Manufacturing Company, Toledo,
Ohio, a corporation of Ohio

Application January 5, 1942, Serial No. 105,016

Term of patent 14 years

To all whom it may concern:

Be it known that I, William I. Smith, a citizen of the United States and a resident of Goshen, Elkhart County, Indiana, have invented a new, original, and ornamental Design for a Velocipede Frame Member, of which the following is a specification, reference being had to the accompanying drawing, forming a part thereof.

In the drawing:

Figure 1 is a perspective view of a velocipede frame member showing my new design; and
Figure 2 is a top plan view thereof.

I claim:

The ornamental design for a velocipede frame member, as shown.

WILLIAM I. SMITH.
